**HOT-GAS RECIPROCATING ENGINES OF THE
DISPLACER PISTON TYPE**

Roelf Jan Meyer, Albert August Dros, and August Albert Liebe, all of Emassingel, Eindhoven, Netherlands, assignors to North American Philips Company, Inc., New York, N.Y., a corporation of Delaware

Filed June 24, 1965, Ser. No. 466,860

Claims priority, application Netherlands, June 23, 1964, 64/06751; July 22, 1964, 64/08345

11 Claims. (Cl. 60—24)

The invention relates to a thermodynamic reciprocating engine of the displacer-piston type, comprising at least one pair of identical cranks each located on one side of a plane going through the center line of the engine and forming part of two crank shafts which rotate in synchronism in co-phase and in relatively opposite directions. The center lines of the shafts are parallel to each other and are located symmetrically one on each side of the plane going through the center line of the engine in a plane at right angles to said center line. Each pair of associated cranks is connected with at least one piston and at least one displacer co-operating with the former, while the connection between each of the cranks and the pistons and displacers respectively includes a piston connecting rod and a displacer connecting rod respectively. The rectilinearly moving parts of the piston connecting rods being located on one side and the rectilinearly moving parts of the displacer connecting rods being located on the other side of the plane going through the center lines of the crank shafts.

The term hot-gas reciprocating engine as used herein not only denotes hot-gas engines but also cold-gas refrigerators and heat pumps, operating on the inverse hot-gas engine principle.

In the known engines of the kind set forth, the synchronization of the two crank shafts is obtained by providing, on each of the crank shafts, a gear wheel so that the two gear wheels engage each other. One of the crank shafts of such a machine is coupled with the driving or the driven machine, whereas the other crank shaft transfers its torque via the gear wheels to the other crank shaft. Apart from the synchronization the gear wheels are therefore used for the transfer of torque. Since the two crank shafts will have unequal inertia moments and since the torque fluctuates, the tooth and bearing tolerances will have to meet very severe requirements in view of the noise level. It will be obvious that the number of revolutions of the engine and that of the driving or driven machine will, in general, differ from each other, so that a comparatively expensive reducing member is required between the crank shaft and the driving or the driven machine.

The invention has for its object to provide an improved structure of the hot-gas reciprocating engine of the kind set forth and is characterized in that the two crank shafts are connected with each other by the provision of a worm and a worm wheel thereon, each of which engages a worm wheel and a worm respectively on a third shaft, which crosses the crank shafts and which establishes a coupling between the hot-gas reciprocating engine and the driving or the driven machine.

An advantage of the construction according to the invention consists in that the worm and worm wheel trans-

2

mission is capable of providing not only the synchronization of the numbers of revolution of the crank shafts, but also, with a suitable choice of the dimensions, a correct transmission ratio between the number of revolutions of the hot-gas reciprocating engine and that of the driven or the driving machine. The expensive reducing gear required in the known construction between the crank shaft and the driven or the driving machine is thus dispensable. A further advantage of the worm and worm wheel transmission is that since simultaneously a plurality of teeth of the worm wheel engage the worm such a transmission gear produces only little noise. This is particularly favorable with hot-gas reciprocating engines which themselves operate substantially without noise or vibrations.

15 A further advantage of the hot-gas reciprocating engine according to the invention resides in that the third shaft can occupy a position in which it is parallel to the plane of the crank shafts. This is particularly advantageous in hot-gas reciprocating engines mounted in a ship in horizontal position, in which case the driving gear is arranged so that the crank shafts are located one above the other and extend substantially parallel to the bottom of the vessel. Under certain conditions it may be desirable for the propulsion to employ a screw driven by a vertical shaft. 20 In accordance with the invention the third shaft can be directly employed to this end.

In a further advantageous embodiment of the hot-gas reciprocating engine according to the invention the third shaft intersects the plane going through the crank shafts. 25 The third shaft (output shaft) may then extend parallel to the center line of the cylinder, in contrast to known structures in which the output shaft crosses the center line of the cylinder at right angles. This may bring about a great advantage, for example, if a hot-gas reciprocating engine has to be built in a low-roofed space, for instance below the bottom of a vessel in horizontal position.

A further embodiment of the hot-gas reciprocating engine according to the invention has the feature that each pair of piston connecting rods has two pistons and each pair of displacer connecting rods has two displacers, said pistons and displacers being all located on the same center line, while the head faces of the pistons and displacers are remote from each other.

A further advantageous embodiment of the hot-gas reciprocating engine according to the invention is characterized in that the engine comprises at least two pairs of associated cranks, each pair of cranks being connected with two pistons and two displacers, the pistons and displacers connected with one pair of cranks having a common center line, the head faces of said pistons and displacers being remote from each other, the center line of the pistons and displacers connected with one pair of cranks being parallel to the center line of those connected with the other pair of cranks. In this way a very compact construction of a four-cylinder hot-gas reciprocating engine is obtained the height of which may be very small.

A further embodiment of the hot-gas reciprocating engine according to the invention is characterized in that it comprises at least two pairs of crank shafts, the crank shafts of each pair being parallel to each other and adapted to rotate in synchronism in opposite directions and in co-phase, while the pairs of crank shafts are arranged in parallel planes at a small distance from each other, so that the crank shafts of one pair cross those

of the other pair. Furthermore, each pair of crank shafts has at least two pairs of associated cranks and each pair of cranks is connected with two pistons and two displacers, the head faces of said pistons and displacers being remote from each other, while those pistons and displacers which are connected with one pair of cranks have one common center line, all common center lines being parallel to each other. The engine comprises a third shaft, which intersects the planes going through the crank shafts and is provided with a widened worm wheel or widened worm or a plurality of worm wheels or worms respectively, which co-operate with worms and worm wheels respectively on each of the crank shafts.

According to a further aspect of the invention a plurality of hot-gas reciprocating engines according to the invention are arranged in line with the third shaft and around the latter in horizontal positions.

According to a further advantageous embodiment the hot-gas reciprocating engine according to the invention comprises two coaxial third shafts, one of which is accommodated at least partly inside the other, the two shafts being provided with one or more worm wheels and worms respectively, which cooperate with worms and worm wheels respectively on the crank shafts of one or more of the hot-gas engines arranged around said shaft. This embodiment has the advantage that two output shafts are available which are capable of rotating with different speeds.

In a further embodiment according to the invention it is possible to choose the angle of the pitch of the worms or the worm wheels on one third shaft so that this shaft rotates in a direction opposite that of the other shaft. This may be of great advantage for propelling ships where the output shafts are provided with screws.

In a further advantageous embodiment of the hot-gas reciprocating engine according to the invention the third shaft intersects the plane(s) of the crank shafts at an angle deviating from 90° while said third shaft is provided with two worm wheels and two worms or a widened worm wheel or a widened worm, which cooperate with worms or worm wheels respectively on the crank shaft. This is favorable for a flat twin engine of the thermodynamic reciprocating type, in which the third shaft is not located in the plane going through the center lines of the two cylinders, but slightly beyond said plane. The distance between the cylinders may then be particularly small, which is advantageous with the space to be occupied. A further advantage resides in that particularly in ships the third shaft leading to the screw must always extend slightly downwards. With known engines this difficulty is solved by arranging the engine itself at an angle. According to the invention the hot-gas reciprocating engine can then be arranged normally in the horizontal position, while the output shaft is at an angle to the horizontal plane.

In a hot-gas reciprocating engine the number of revolutions of the engine will usually be higher than that of the driven machine. For this reason the crank shafts of a hot-gas reciprocating engine will usually be provided with worms, while the third shaft will be provided with a worm wheel. In contrast thereto, the number of revolutions of a cold-gas refrigerator will usually be lower than the number of revolutions of the driving machine. In these machines the third shaft will usually be provided with a worm and the crank shafts will have worm wheels.

The invention will be described more fully with reference to the drawing, in which a number of hot-gas reciprocating engines are shown by way of example.

FIGS. 1, 2 and 3 are three cross sections of a hot-gas reciprocating engine.

FIGS. 4 and 5 show diagrammatically a four-cylinder hot-gas engine, the former in cross-section and the latter in elevation.

FIG. 6 shows diagrammatically an advantageous arrangement of an eight-cylinder hot-gas engine.

FIGS. 7 and 8 show an eight-cylinder hot-gas engine in which the cylinders are arranged around the output shaft.

FIGS. 9 and 10 show a two-cylinder hot-gas engine in which the output shaft is parallel to the plane going through the crank shafts.

Referring to FIGS. 1, 2 and 3 reference numeral 1 designates a cylinder, in which a displacer 2 and a piston 3 are adapted to reciprocate with phase difference. The piston 3 varies, during its displacement, the volume of a compression space 4 and the displacer varies with its head face the volume of an expansion space 5. The compression space 4 and the expansion space 5 communicate with each other through a cooler 6, a regenerator 7 and a heater 8. Heat is supplied to the head of the cylinder 1 and the heater 8 through a burner 9. The piston 3 is connected through a piston rod 10 with a yoke 11. The displacer 2 is connected through a displacer rod 12 with a yoke 13. The yoke 11 is connected via piston connecting rods 14 with the cranks 15 of the crank shafts 16. The yoke 13 is connected through displacer connecting rods 17 also with the cranks 15. The crank shafts 16 are provided with worms 18, which cooperate with a worm wheel 19 on a third shaft 20. The third shaft 20 is coupled with a shaft 21 of a driven machine 22. In operation the torque of the crank shafts 16 will be transferred through the worms 18 to the worm wheel 19 and hence to the output shaft 20. It will be obvious that the worms 18 and the worm wheel 19 have a double function i.e. the synchronization of the crank shafts 16 and the transfer of torque from the crank shafts 16 to the driven shaft 20.

From the drawing it will furthermore be seen that the number of revolutions of the crank shafts 16 is higher than that of the driven machine 22. This reduction of the number of revolutions is achieved without the need for a comparatively expensive reduction gear. The desired transmission ratio in this hot-gas engine is obtained by a correct choice of the cooperating worms 18 and the worm wheel 19.

An advantage of this hot-gas engine is that the center line of the cylinder 1 and that of the driven machine are parallel to each other, so that a horizontal hot-gas engine may be constructed with a very small height. This is important for example in ships, where the engine may be accommodated below the floor.

FIGS. 4 and 5 show diagrammatically a four-cylinder hot-gas engine. The cylinders are designated by 31, 32, 33 and 34. The continuous crank shafts 35 are provided with worms 36, which cooperate with the worm wheel 37. The worm wheel 37 occupies an oblique position and is widened, so that the output shaft 38 is at an angle to the plane going through the center lines of the cylinders. The resultant construction is a hot-gas engine which also has a very low structural height and which is particularly suitable for being accommodated below the floor of a vessel or water craft. A further advantage of this construction is that the shaft 38 is at an angle to the plane going through the cylinders. The cylinders 31 and 32 may therefore have a smaller distance between their center lines than in the case in which the shaft 38 is located in the plane of these cylinders.

A further advantage is that the shaft 38 can be directly coupled with a machine located slightly outside the plane going through the center lines of the cylinders. This may be the case in ships in which the engine is located at a higher level than the screw. According to the invention it is now possible to couple the engine directly with the screw through the shaft 38, without the need for an oblique position of the engine. It will be obvious that the crank shafts 35 may be extended at will on both sides and may be provided with cranks. The engine may thus be extended on either side and further pairs of cylinders, so that eight or twelve cylinder hot-gas engines are obtained. FIG. 6 shows diagrammatically the possibility of providing a third shaft 40 with for example two worm wheels 41 and 42, with which worms 43 and 44 co-

operate, arranged on crank shafts 45 and 46 respectively. These crank shafts 45 and 46 are provided with cranks forming part of rhombic driving gears of hot-gas engines. This provides an arrangement which is particularly suitable for accommodation in a low-roofed, narrow space.

FIGS. 7 and 8 show a hot-gas engine having two output shafts 50 and 51. The shaft 50 is accommodated for the major part inside the hollow shaft 51. The two shafts 50 and 51 are provided with worm wheels 52 and 53 respectively, with which co-operate the worms 54 and 55 respectively. The worms 54 are provided on the crank shaft 56 forming part of the driving gears of the hot-gas engine cylinders 57 and 58. The worms 55 are arranged on the crank shafts 59, which form part of the driving gears of the hot-gas engine cylinders 60 and 61. The pitch angle of the worms 54 may be chosen so with respect to the pitch angle of the worms 55 that the shafts 50 and 51 rotate in the same directions. The worms concerned may, however, also be chosen so that the shafts 50 and 51 rotate in opposite directions, which may be important for the propulsion of ships. From FIG. 8 it will be seen that the cylinders 57, 58 and 60, 61 are arranged symmetrically around the center of the engine. In this manner a very compact construction of the hot-gas engine is obtained, which is extremely suitable for accommodation in a cylindrical, elongated space.

FIGS. 9 and 10 show two cylinders 90 and 91 of a hot-gas engine. In each of these cylinders the pistons 92 and displacers 93 are capable of reciprocating with phase difference. During the movement of said members the volumes of a compression space 94 and of the expansion space 95 are varied. Said spaces communicate with each other through a cooler 96, a regenerator 97 and a heater 98. Each of the pistons and displacers is connected through a piston rod 100 and a displacer rod 101 respectively with a rhombic driving gear.

This rhombic driving gear comprises the yokes 103 and 104 with which the pistons and displacers respectively may be coupled. The yokes 103 and 104 are connected in turn by connecting rods 105 and 106 respectively with cranks of the crank shafts 107. The crank shafts 107 are provided with worms 108, which co-operate with worm wheels 109 on a third shaft 110. The third shaft 110 is coupled through gear wheels 113 with the machine to be driven. In the drawing the driven machine is formed by the screw 112, journaled in a housing 114, which may be rotatably connected with the ship's floor.

In the operation of the hot-gas engine shown the piston and displacer movements are transferred through the yokes 103 and 104 respectively and connecting rods 105 and 106 respectively to the crank shafts 107 and the movement of the crank shafts is transferred through the worms 108 and the worm wheels 109 to the output shaft 110. This provides an extremely simple coupling between the crank shafts and the output shaft and by suitable choice of the worms and the worm wheels the correct transmission ratio is obtained. The worms and worm wheels ensure furthermore that the crank shafts rotate in synchronism and in opposite directions. It should be noted here, that, since the crank shafts rotate in opposite directions, the pitches of the two worms or of the two worm wheels must be opposite each other. Although in the embodiment the two worm wheels and worms have equal diameters, one worm wheel may have a larger diameter than the other, so that the worm co-operating with the worm wheel of larger diameter must have a smaller diameter than the other worm. The shaft 110 will then occupy a slightly oblique position.

As is shown in the drawing, the hot-gas engine according to the invention is particularly suitable for accommodation in a low-roofed space, for example below the floor of a ship.

Although the drawing shows only hot-gas engines, it will be obvious that a worm and worm wheel transmission may also be effectively used in cold-gas refrigerators of the displacer type. In this case the third shaft will

usually have a worm, while the crank shafts are provided with worm wheels, so that the driven machine has a higher speed than the cold-gas refrigerator.

What is claimed is:

- 5 1. A hot-gas reciprocating engine adapted for driving a driven element comprising; at least one cylinder, at least one piston and at least one displacer adapted for reciprocation in said cylinder with a relative phase difference, at least one pair of identical cranks, at least two crankshafts, said cranks being located each on one side of a plane extending through the center line of said engine and forming part of said two crankshafts, said crankshafts being rotated in the same phase, in synchronism and in relatively opposite directions, the center lines of said shafts being parallel to each other and being located symmetrically, each on one side of the plane going through said engine in a plane at right angles to the center line of said engine, each pair of associated cranks being connected with at least one piston and at least one displacer, at least one piston connecting rod connecting said piston and the respective crank, at least one displacer connecting rod connecting said displacer and the respective crank, the rectilinearly moving parts of said piston connecting rods being located on one side and the rectilinearly moving parts of the displacer piston being located on the other side of the plane extending through the center lines of said crank shafts, a worm mounted on each of said crankshafts, and another shaft provided with a worm gear which couples said hot-gas reciprocating engine with said driven element.
- 10 2. A hot-gas reciprocating engine as claimed in claim 1 wherein said other shaft is at least substantially parallel to the plane extending through said crank shafts.
- 15 3. A hot-gas reciprocating engine as claimed in claim 1 wherein said other shaft intersects the plane extending through said crank shafts.
- 20 4. A hot-gas reciprocating engine as claimed in claim 1 wherein each pair of piston connecting rods is connected to two pistons and each pair of displacer connecting rods is connected to two displacers, said pistons and displacers having a common center line, and the head surfaces of said pistons and displacers being remote from each other.
- 25 5. A hot-gas reciprocating engine as claimed in claim 1 wherein said engine comprises at least two pairs of associated cranks, each pair of cranks being connected with two pistons and two displacers respectively, the pistons and displacers connected with one pair of cranks having a common center line, and the center line of said pistons and displacers connected with one pair of cranks being parallel to the center line of said pistons and displacers connected with the other pair of said cranks.
- 30 6. A hot-gas reciprocating engine as claimed in claim 1 wherein said engine comprises at least two pairs of crankshafts, the crankshafts of each pair being parallel to each other and rotating in synchronism, in co-phase and in opposite directions, the pairs of crankshafts being arranged in parallel planes spaced apart by a relatively small distance so that one pair of crankshafts cross the other pair of crankshafts, each pair of crankshafts comprising at least two pairs of associated cranks, and each pair of cranks being connected with two pistons and two displacers.
- 35 7. A hot-gas reciprocating engine as claimed in claim 6 wherein said engine is provided with said other shaft around which a plurality of engines are arranged parallel to the longitudinal axis of said other shaft.
- 40 8. A hot-gas reciprocating engine as claimed in claim 7 wherein said engine is provided with two co-axial other shafts, one of said shafts being located at least partly inside the remaining shaft, said two other shafts being provided with at least one worm, and a worm gear connected to each of said engines.
- 45 9. A hot-gas reciprocating engine as claimed in claim 8 wherein said worms on at least one of said other shafts
- 50 70 75

has such an angle of pitch relative to said worm on the remaining other shaft that in operation the said two other shafts rotate in opposite directions.

10. A hot-gas reciprocating engine as claimed in claim 1 wherein said other shaft intersects the plane extending through the crankshafts at an angle less than 90°, said other shaft being provided with at least one worm gear, and a worm connected to each of said crankshafts, said worms co-acting with said worm gear.

11. A hot-gas reciprocating engine as claimed in claim 10 wherein said other shaft is at an angle of not more

than 15° to the plane extending through the center lines of said piston and displacer.
